UNITED STATES PATENT OFFICE.

LERoy H. ARTER, OF WARREN, OHIO.

SHOE-SHINING CABINET.

1,346,585.

Specification of Letters Patent. Patented July 13, 1920.

Application filed March 18, 1916. Serial No. 85,016.

To all whom it may concern:

Be it known that I, LEROY H. ARTER, a citizen of the United States, residing at Warren, in the county of Trumbull and State of Ohio, have invented a certain new and useful Improvement in Shoe-Shining Cabinets, of which the following is a full, clear, and exact description, reference being had to the accompanying drawings.

10 This invention relates to an improved combined shoe shining cabinet and foot support that is especially adapted for attachment to a wall or other vertical supporting surface; and the invention has for 15 its objects to provide a cabinet of the aforesaid nature that is neat in appearance; that is durable; that may be folded against the wall where it is entirely out of the way; which may contain the usual shoe shining 20 equipment comprising a brush or buffer, a dauber, polish, etc.; and which may be swung down into operative position to form a strong support for the foot of the user, and adjusted to various elevations to accommodate persons of different heights.

25

The foregoing objects, and others which will become apparent as this description proceeds, are attained in the construction illustrated in the accompanying drawing 30 which forms part hereof and wherein Figure 1 is a perspective of the shoe shining cabinet in operative condition; Fig. 2 is a similar view of the cabinet in inoperative condition; Fig. 3 is a central vertical section through the cabinet, the plane of the 35 section being indicated by the line 3—3 of Fig. 4; and Fig. 4 is a horizontal section on the line 4—4 of Fig. 3.

While I will proceed to describe the construction illustrated herein in detail, I wish 40 to be understood as not limiting myself to the structural details thereof further than is required by the terms of the annexed claims and is rendered necessary by the 45 state of the prior art.

I prefer to construct the entire cabinet of metal, and as shown herein the same comprises a wall plate 1, the lateral edges of 50 which are turned forward and then inward to produce opposed channels 2. The bottom of the plate is curved outward at 3 to close the bottoms of the channels 2, and the body portion of the plate is ribbed vertically at 4, so that the faces of the ribbed portions 55 are projected a slight distance in advance of

the surface of the body portion of the plate, for a purpose which will be presently explained. The plate 1 is provided with apertures 5 for the reception of screws whereby the plate may be secured to a wall or other 60 vertical support.

A box or casing 8 is slidably and hingedly connected to the plate 1 by means of a rod 9 which extends through the end of the box adjacent the aforesaid plate and has its 65 ends contained within the channels 2. The ends of the rod 9 may or may not be turned at right angles to its body portion, as shown at 10, it being considered preferable to extend the ends of the rod along the channels 70 for a sufficient distance to prevent the rod from turning out of transverse alinement with the plate 1, although the fit of the casing or box 8 between the opposed edges of the channels 2 may be sufficiently close 75 to prevent an action of this sort. The upper edge of the end 11 of the box is curved inward substantially concentric to the rod 9 so that the box may swing with freedom between its vertical and horizontal positions. Lugs 12 are struck out of the end 11 for coöperation with series of holes 13 in the ribs 4, the lugs being permitted to extend materially through the holes because of the offset between the surfaces of the 80 ribs 4 and the body portion of the plate. It is understood of course that any suitable equivalent may be substituted for the lugs 12, although the construction just described and illustrated in the drawing is considered 85 thoroughly satisfactory. On the other hand, I find, in my experiments, that it is not absolutely necessary to employ any sort of interlocking parts between the box and wall plate, for if the parts are made to fit accurately, the thrust of the pin 9 against the flanges of the channels 2, and the opposed pressure of the lower edge of the end wall 11 against the plate 1 when the weight of 90 the foot is applied to the outer end of the box, create sufficient binding to prevent 95 movement between the box and plate.

A cover 15 is hinged to the box 8, and the hinge connection is preferably accomplished by turning lugs 16 downward over the sides 100 of the box and perforating them for application to the rod 9. For strength and neatness of appearance, the edges of the cover 15 are turned downward over the sides of the box, as shown at 17, and the ends of the 110

down-turned portions, opposite the lugs 16, are enlarged at 18 so that, when the box is folded upward against the plate 1, the enlargements 18 will engage the edges of the 5 channels 2, thus preventing any possibility of the edges of the cover dropping behind the front flanges of the channels and catching, as the box is swung downward. The cover 15 is shown as closing only about one- 10 half of the box, although it is understood that the same might be made to extend the full length thereof. I desire, however, to close the forward end of the box by a cover 20, similar to the cover 15, and hinged to 15 the sides of the box by rivets 21 which extend through lugs 22 formed at one end of the side flanges 23 of the cover, the opposite ends of the flanges having enlargements 24, which have the same function as the en- 20 largements 18 of the former cover. The cover 20 is intended as a rest for the front portion or sole of a shoe, during the shining operation, and the surface of the cover may therefore be roughened, as indicated at 25, 25 or otherwise treated to prevent the shoe slipping, it being understood of course that the shoe is worn while performing the shining operation. The forward or free end of the cover 20 has ears 26 which overhang and 30 may frictionally engage the forward end of the box, to retain the cover closed, and the forward end of the rear cover 15 is provided with a central notch 27 by which the cover may be grasped to raise the same.

35 A pair of spring clips 30 are attached to the opposite side walls of the box, adjacent its hinged end and near the bottom, in a position to grip a box of polish, represented at 31. The style of the clips and their re- 40 siliency make them adjustable to various sized boxes. The rest of the shoe shining equipment, which may comprise a dauber 32 and a buffer 33, may be stored within the forward end of the box. When the box is 45 folded into inoperative position, as shown in Fig. 2, the projection 35 of a spring tongue 36, which may be formed integral with and extends forwardly of the upper end of the plate 1, enters a depression 37, in the end 50 wall 38 of the box.

When it is desired to use the cabinet, the upper end of the box 8 may be grasped and drawn forward to free it from the tongue 36. The box may then be elevated by sliding 55 the ends of the rod 9 upward within the channels 2 until the desired height is reached to best accommodate the height of the person intending to use the cabinet. By swinging the box to horizontal position, the 60 lugs 12 may be inserted through the corresponding holes 13 of the two ribs 4 to hold the box against sliding downward when the weight of the foot is upon the free end of the box. The dauber and buffer may be re- 65 moved by opening the cover 20, the cover be-

ing thereafter closed for the support of the foot. The cover 15 may be left open during the shining operation so that access to the polish may be had at any time. When the shining operation is completed and the buffer and dauber are replaced within the box, the free end of the box may be lifted enough to remove the lugs 12 from the holes 13, after which the hinged end of the box will drop to the lower end of the plate, and the free end thereof may be swung upward and snapped beneath the tongue 36.

Having thus described my invention, what I claim is:—

1. A device of the character set forth comprising a supporting plate having its lateral edges bent to produce a pair of opposed guides, a member having portions slidable within said guides, a foot support hingedly connected to said member and capable of swinging between a plane substantially parallel to said guides and a plane at substantially right angles thereto, and means which is effective when the support is at substantially right angles to the guides for retaining the support at various elevations with respect to the guides. 80

2. A device of the character set forth comprising a wall plate having its lateral edges bent forward and inward to produce opposed channels, and a foot support hingedly and slidably connected to said channels and capable of swinging between planes substantially parallel to and at substantially right angles to said plate, the foot support 95 and the plate having portions which engage, when the foot support occupies any desired position along the plate and is at substantially right angles thereto, for preventing relative movement between the foot support 100 and plate. 105

3. A device of the character set forth comprising a plate for attachment to a vertical surface and having its lateral edges bent forward and inward to produce opposed channels, a rod having its ends guided within said channels, a foot support hingedly connected to the rod, the plate and support having portions which engage to prevent relative vertical movement between 110 said support and plate when the support is at any desired position along the plate and is at substantially right angles to the plate. 115

4. A device of the character set forth comprising a supporting plate having its lateral edges turned forward and inward to produce opposed channels, a rod having its ends guided within the channels, and a foot support through one end of which said rod extends whereby the foot support is hingedly connected to the rod, the plate having a series of holes and the foot support a lug that is adapted to enter any one of said holes when said foot support is swung to a position at right angles to the plate, thereby 125 130

to prevent relative movement between the support and plate while in such position.

5. A device of the character set forth comprising a plate having its lateral edges bent forwardly and inwardly to produce opposed channels, a rod having its ends guided within said channels, a box through the side walls of which said rod extends thereby hingedly connecting the box to the 10 rod, and a cover for said box having lugs which depend along opposite sides of the box and are perforated for attachment to the aforesaid rod, the box and plate having portions which engage when the box is at 15 substantially right angles to the plate to prevent relative movement between the box and plate.

6. A device of the character set forth comprising a plate having its lateral edges bent forwardly and inwardly to produce opposed channels, and having its lower end bent forward to form a stop, and a spring tongue extending forwardly from the upper end of the plate, a rod having its ends guided within the aforesaid channels, a box through which the aforesaid rod extends thereby hingedly connecting the box to the 20 rod, a cover for the box that is provided with depending perforated ears for application to the aforesaid rod, the plate having a vertical series of apertures and the end of the box adjacent to the plate having a projection which is adapted to enter any one of 25

the aforesaid apertures when the box is at substantially right angles to the plate, 30 thereby to prevent relative movement between the box and plate when the box is in such right angled position, the opposite end of the box and the aforesaid spring tongue having portions which interengage when 35 the box is substantially parallel to the aforesaid plate, to maintain the parts in such position.

7. A device of the character set forth comprising a plate having its lateral edges bent forwardly and inwardly to produce opposed channels, and having its lower end bent forward to form a stop, a rod having its ends guided within the aforesaid channels, a foot support hingedly connected to 40 the rod, the plate having a vertical series of apertures and the adjacent end of the support having a projection which is adapted to enter any one of the aforesaid apertures when the support is at substantially 45 right angles to the plate, thereby to prevent relative movement between the support and plate when the support is in such right angled position, the opposite end of the support and the upper end of the plate having 50 portions which interengage when the support is substantially parallel to the plate, to maintain the parts in such position.

In testimony whereof I hereunto affix my signature.

LEROY H. ARTER.
